UNITED STATES PATENT OFFICE.

FREDERICK C. OVERTURY, OF HILLSDALE, NEW JERSEY, ASSIGNOR TO THE FLINT-KOTE COMPANY, OF BOSTON, MASSACHUSETTS, A CORPORATION OF MASSACHUSETTS.

ROOF.

Application filed November 8, 1921. Serial No. 513,664.

This invention relates to roofing of that type commonly constructed of felt impregnated with asphalt and coated with a heavy asphalt on which are spread and partially embedded particles or granules of slate or other suitable surfacing material which gives color to the roofing and adds to its weather and fireproofing qualities. This roofing is of comparatively thin material and unless 10 special coloring or methods of laying are resorted to, presents a flat, uninteresting appearance, giving an unsubstantial and cheap effect. One method of relieving this flat appearance to some extent is by laying the roof 15 in a series of overlapping courses or strips, these strips being cut if desired at their lower edges to simulate the butts of shingles.

Another method which has been proposed 20 is to produce shadow effects by variously coloring the material. This may be done by rolling the granular surface material into the asphalt coating while plastic to a greater extent where shadow effects are desired than at other places so that the asphalt flows between the surfacing particles, filling the interstices and becoming more or less visible on 25 the surface depending on the pressure used. As the asphalt is black this action causes the roof to appear darker at the portions subjected to greater pressures, giving the effect 30 of showing the same color as the rest of the material under less favorable light conditions. This rolling also produces a surface effect in low relief, the portions which appear 35 darker being somewhat depressed below the level of the lighter colored portions.

According to the present invention the roofing is composed of overlying courses, the surface level of the exposed portions being 40 depressed sharply about the entire exposed margin of the overlying course and tapering therefrom to its normal level. This insures the raising of the exposed margins above the level of the adjacent underlying material and 45 greatly enhances the apparent thickness of the edge. This appearance is further heightened by the shadow effect produced by the darker coloring effected by the localized pressure in the manner above described.

50 This construction makes possible a much more marked appearance of substantial construction than has hitherto been found possible with this type of roofing.

55 For a more complete understanding of this invention, together with further objects and

advantageous details and combinations of parts, reference may be had to the accompanying drawings in which—

Figure 1 is a plan of a portion of a roof 60 constructed according to this invention.

Figures 2 and 3 are sections on lines 2—2 and 3—3, respectively, of Figure 1.

Figure 4 is a plan of a portion of a single strip.

Figure 5 is a section on line 5—5 of 65 Figure 4.

Referring more particularly to Figures 4 and 5 each strip of roofing 1 is cut along its lower margin in any form desired a repeated pattern being usual. As illustrated this 70 form comprises tabs 2 simulating the lower ends of ordinary wooden shingles, these tabs being formed by spaced slots 3 extending inwardly from the lower edge of the strip. Somewhat above the upper end of the slots 3 75 the lower edge of a succeeding overlying course is to be positioned with its slots staggering the slots 3. Defining the position of the edge of this overlying strip the surface of the strip 1 is impressed sharply as at a 80 as by passing the strip under suitably formed impression rolls, forming in low relief a series of tabs 4 separated by narrow depressions 5 corresponding in shape and size to the slots 3, assuming that the overlying strip 85 is of the same contour as strip 1. This impression of the surface of the material is preferably effected while the asphalt coating is still plastic so that it flows between the 90 particles of coating material to show on the surface thereof, this causing the strip to appear darker at the depressed portions and giving a desired shadow effect.

The depressed portion rises gradually from a below the margin of the portions 4 until it 95 merges with the normal level of the strip as shown at b in Figure 5. The portions 5 are depressed to the maximum extent throughout their entire area as shown between a and c in Figure 5, while the tabs 4 are undepressed, the surface thereof being level with that of the tabs 2. A plurality of such strips are superposed in overlying courses as shown in Figures 1, 2, and 3, the tabs 2 of each 100 overlying course mating the relief portions 4 of the underlying course so that the sharply depressed portions a of each course are positioned directly next to the lower edge of the adjacent course as shown in Figures 2 105 and 3 and the depressions 5 underlie the slots 110

3. This causes the tabs 2 at their margins to be spaced above the adjacent surface of the underlying course the amount to which this surface is depressed below the general 5 level of the strip. Each course also is thus clearly marked to show the position of a succeeding course which adds to the facility with which the roof may be laid.

Due to the fact that the upper surface of 10 the material is rough, the courses do not lie closely superposed so that by this construction an apparent thickness of the shingle butts, caused by the thickness of the tabs 2 added to the relief of the portions 15 4, may be substantially twice the thickness of the strip material without dangerously thinning the material at the depressed portions. While as herein shown the roofing is composed of strips, either extending 20 continuously across the roof or in the form of shorter sections, it being common in the art to employ sections having four tab portions, the same idea might also be exemplified with individual shingles, it being only 25 necessary for the purpose of this invention to depress the surface of the underlying course sharply about the margin of the overlying course and tapering gradually upward away from this margin, this depressed portion 30 being shaded as above described to give an added shadow effect. It is also evident that the lower edge of material might be cut in any shape desired and that the edges of overlying courses might be of different 35 shape or pattern if desired.

Having thus described an embodiment of this invention it should be evident that many changes and modifications might be made therein without departing from its spirit 40 or scope as defined by the appended claims.

What I claim is:—

1. A roof composed of overlapping courses of material, the exposed surface portions of each course lying adjacent the edges of the 45 overlying courses being depressed below the normal level of the remaining surface portions, and the portions beneath said overlying course being at the normal level.

2. A roof composed of overlapping courses 50 of strip material, the exposed surface portions of each course lying adjacent the edges of the overlying course being depressed below the normal level of the remaining surface portions, and the portions beneath said overlying course being at the normal level.

3. A roof composed of overlapping courses 55 of material, the exposed surface portions of each course lying adjacent the edges of the overlying courses being depressed below the normal level of and of a darker shade than the remaining surface portions and the portions lying beneath the overlying course being at the normal level.

65 4. A roof composed of overlapping courses

of strip material, the exposed surface portions of each course lying adjacent the edges of the overlying course being depressed below the normal level of and of a darker shade than the remaining surface portions 70 and the portions lying beneath the overlying course being at the normal level.

5. A roof composed of overlapping courses of material, the exposed surface portions of the courses being sharply depressed below 75 the remaining surface around the exposed margin of the overlying course and gradually rising and merging with the remaining surface away from said margin.

6. A roof composed of overlapping courses of material, the exposed surface portions thereof being sharply depressed below the remaining surface around the exposed margin of the overlying course and gradually rising and merging with the remaining surface away from said margin, the depressed portions being of darker shade than the remainder of said surface.

7. A strip shingle comprising a strip cut on its lower edge in a repeated pattern, and having above said edge the same pattern in staggered relation to said edge impressed in the surface thereof to sharply mark the location of the lower edge of a superposed strip, said impression merging gradually to the normal level of the surface toward the lower edge of said strip.

8. A strip shingle comprising a strip cut on its lower edge in a repeated pattern, and having above said edge the same pattern in staggered relation to said edge impressed in the surface thereof to sharply mark the location of the lower edge of a superposed strip, said impression merging gradually to the normal level of the surface toward the lower edge of said strip, said impressed portion being of darker shade than the remainder of said strip surface.

9. A strip shingle comprising a strip cut on its lower edge in a pattern and having above said edge a pattern of the lower edge of a second strip to be superposed on said strip impressed in the outer surface thereof, said impressed pattern being sharply defined at its upper edge and at its lower edge merging into the remaining surface of said strip.

10. A strip shingle comprising a strip cut on its lower edge in a pattern and having above said edge a pattern of the lower edge of a second strip to be superposed on said strip impressed in the outer surface thereof, said impressed pattern being sharply defined at its upper edge and at its lower edge merging into the remaining surface of said strip, said impressed portion being of darker color than the remainder of said strip.

11. A strip shingle comprising a strip notched at its lower edge to define shingle.

simulating tabs, the surface of said strip being depressed above said lower edge to correspond with the lower edge of an overlying similar strip having its notches staggered with respect to the notches of said strip, the upper edge of said depression being sharply defined, and the lower edge merging into the undepressed surface.

12. A strip shingle comprising a strip notched at its lower edge to define shingle simulating tabs, the surface of said strip being depressed above said lower edge to correspond with the lower edge of an overlying similar strip having its notches staggered with respect to the notches of said strip, the upper edge of said depression being sharply defined, and the lower edge merging into the undepressed surface, said depressed surface being of darker color than that of the remainder of the surface.

13. A prepared roofing shingle element comprising a fibrous foundation layer, an asphalt coating and a grit surface having its said grit surface depressed and the underlying asphalt coating molded to provide an abrupt forwardly facing transverse shoulder extending throughout the width of the shingle element at the inner margin of its weather end.

14. A prepared roofing shingle element comprising a fibrous foundation layer, an asphalt coating and a grit surface having its said grit surface depressed and the underlying asphalt coating molded to provide an abrupt forwardly facing transverse shoulder extending throughout the width of the shingle element at the inner margin of its weather end, and a sloping surface portion extending forwardly in front of the said shoulder and merging gradually with the flat upper surface of the shingle element in its said weather end.

15. A shingle element having its upper surface at the inner end of its weather por-

tion and at the outer end of its covered portion relatively offset to provide an abrupt forwardly facing transverse shoulder extending throughout the width of the shingle element at the inner margin of its said weather portion.

16. A prepared roofing shingle element comprising a fibrous foundation layer and an asphalt coating of uniform thickness throughout the exposed and covered portions of the shingle element except at the inner end of the exposed portion of the shingle where its said asphalt coating is of reduced thickness to provide an abrupt forwardly facing transverse shoulder extending throughout the width of the shingle element.

17. A roof covering comprising, in combination, a plurality of partially overlapping courses of shingles and spacing means integral with the covered portion of each course and supporting the free edges of the shingles of each course above the level of the immediately adjacent exposed surface of the shingles of the next lower course.

18. A roof covering comprising, in combination, a plurality of partially overlapping courses of shingles, the shingles of each course having a forwardly facing transverse shoulder aligned with the free edges of the shingles of the next higher course.

19. A roof covering comprising, in combination, a plurality of partially overlapping courses of shingles, the shingles of each course having a forwardly facing transverse shoulder aligned with the free edges of the shingles of the next higher course and a sloping surface portion extending forwardly in front of the said shoulder and merging gradually with the flat exposed upper surfaces of the shingles.

In testimony whereof I have affixed my signature.

FREDERICK C. OVERBURY.
